UNITED STATES PATENT OFFICE

HANS DEUTSCH, OF VIENNA, AUSTRIA, ASSIGNOR TO FIRM: ALEX FRIEDMANN, OF VIENNA, AUSTRIA

BOILER FEED APPARATUS WITH EXHAUST STEAM PREHEATER

Application filed January 6, 1930, Serial No. 418,909, and in Austria January 8, 1929.

It is known that exhaust steam preheaters, more particularly those which are employed with locomotives, do not give the full theoretical attainable efficiency, since the theory 5 assumes that the whole of the water to be evaporated is fed under conditions in which the regulator or throttle of the locomotive is open, that is, when exhaust steam is available.

10 This assumption is not strictly justified, since a portion of the feed water must be delivered into the boiler when the locomotive regulator or throttle is closed; this water cannot in the usual constructions be heated 15 by exhaust steam, because, when the locomotive regulator or throttle is closed, there is no exhaust steam.

Devices are known with the object to preheat the feed water by exhaust steam, even 20 when the locomotive regulator or throttle is closed, in which by the provision of a hot water container there is a supply of water which is heated by exhaust steam when the 25 steam valve is open, but which is fed into the boiler only when the locomotive regulator or throttle is closed.

The restricted space conditions on a locomotive, however, make it impossible to provide a hot water container sufficiently large 30 to contain, when the locomotive regulator or throttle is closed, the quantity of water required for all cases. A certain deficit must almost always be pumped from the cold water container, in order to bring the lowered 35 level of the boiler water to the required height.

The above-mentioned feeding devices with the inserted hot water container must necessarily be so constructed that the staff have 40 only to operate one or two handles and that the apparatus otherwise acts automatically; when the locomotive regulator or throttle is open, water is delivered, as required, either 45 from the cold water container into the boiler or into the hot water container; with the valve closed, on the other hand, from the hot water container into the boiler. Also, in 50 spite of the various different conditions of feeding the water, the apparatus should re-

quire no extreme attention on the part of the staff.

Previously known devices of the type described allow only the following three variations of the feed: 55

1. With the locomotive regulator open, the boiler can be fed from the cold water container.

2. With the locomotive regulator open, the hot water container can be fed from the cold 60 water container.

3. With the locomotive regulator closed, the boiler must be fed from the hot water container.

In this way the feed apparatus is incomplete, since cases can occur in which the apparatus is not in a position to deliver water to the boiler and particularly with the steam valve closed when the hot water container has been already emptied, before the 70 water level in the boiler has attained the required height. 65

My invention consists in an apparatus which obviates this drawback and in which, when the locomotive regulator is closed, the 75 boiler can be fed by preheated water, both from the cold water container and also from the hot water container, the same apparatus also at the same time permitting, with the locomotive regulator open, the boiler to be 80 fed from the cold water container and also the hot water container to be charged without requiring any additional feeding apparatus, or involving a more inconvenient manipulation than the usual feeding devices. 85 The above-mentioned drawback is completely obviated, and the feeding apparatus is arranged to comply with all the required conditions without necessitating the provision of a second feeding device. 90

The accompanying drawings illustrate an example of an apparatus according to the invention, in which

Fig. 1 shows the arrangement on the locomotive; 95

Fig. 2 is a section through the exhaust steam injector and a junction box in connection with the injector; and

Fig. 3 shows a feeding box which is preferably used with this apparatus. 100

In Fig. 1, 1 represents an exhaust steam injector in which automatically operating valves are inserted, connected by pipes 5, 6, 8, 9 and 10 with the junction box 16.

5 The junction box 16 is connected by pipe 7 and a closing device 21 to the steam space of the boiler. Two feeding paths lead from it also to the boiler. The boiler can also be fed from the junction box by a pipe 13 and feed 10 box 19 and by a pipe 14 which leads to the hot water container 18 from which a pipe 20 is connected to the boiler by a feed valve 22. From the exhaust steam injector 1, the pipe 10 leads to a valve 17 called afterwards the 15 supplementary valve. The valve is connected by branch pipes 11 and 12, respectively, with the junction box 16 and the hot water container 18.

The exhaust steam from the working cylinder of the locomotive, after passing the oil extractor 15, is led through a pipe 3 to the exhaust steam injector, which receives water from the tender through a pipe 2. The live steam is led from the cylinder through 25 a pipe 4 which leads to branches 5 and 6, said branches leading in their turn to the exhaust steam injector and to the junction box 16, respectively.

30 The positions of the valve shown in Fig. 2 correspond to the case in which the boiler is fed from the cold water container with the locomotive regulator closed, while at the same time the hot water from the container 18 can flow to the boiler.

35 The apparatus can operate under four different working conditions under which the boiler is to be fed.

1. The boiler is to be fed with the locomotive regulator closed. In this case there are 40 three different ways possible:

a. With the control valve 23 open and the supplementary valve 17 closed, the contents of the hot water container 18 can be discharged into the boiler.

45 b. Both the control valve 23 and the supplementary valve are opened, so that at the same time hot water from the container flows to the boiler and water from the tender is delivered into the boiler by means of live 50 steam.

c. The control valve 23 and the supplementary valve 17 are opened; the container 18 has been, however, already emptied and the boiler is only fed by water from the tender directly introduced into the boiler by means of live steam.

55 2. The regulator of the locomotive is closed and boiler feed is not required. In this case both valves 23 and 17 are closed.

60 3. The locomotive regulator is open and boiler feed is not required. In this case both valves 23 and 17 are closed and 24 opened, so that the exhaust steam only delivers water into the container.

65 4. The locomotive regulator is open and

boiler feed is required. The control valve 23 is opened and valve 24 is closed, the supplementary valve 17 is closed. The injector then feeds water from the tender by means of exhaust steam and live steam into the boiler.

70 The apparatus shown in Fig. 2 fulfils its purpose under these four working conditions. Its arrangement and working are described in the following:

75 1a denotes the working condition in which the boiler is fed with hot water from the container with the locomotive regulator closed. The control valve 23 must be opened and the supplementary valve 17 closed. The live steam is taken from the boiler through the steam inlet 21 (Fig. 1) and flows through the pipe 7 and the valve 23 into the chamber 44. The steam pressure lifts the valve 26 and presses it on its upper seat. This is possible 80 because the locomotive regulator is closed and there is no pressure in the pipes 4, 5 and 6 and in the chamber above the valve 26, in which the non-return valve 35 is connected with the valve 26. The steam now enters through an opening 36 into the pipe 11 and from there passes through the pipe 12 into the container 18, so that the latter is under the boiler pressure. Hot water can now flow from the container 18 through the pipe 20 and the feed 85 box 22 to the boiler.

90 Under the working condition denoted by 1b, the boiler is to be fed with water from the tender by live steam at the same time is fed with water from the container 18. In this case, both the control valve 23 and the supplementary valve 17 must be open. Steam enters 95 through the pipe 11 into the pipe 10 and acts on the exhaust steam injector, the valve 29 being moved to the left and held down on its left seat. There is, therefore, boiler pressure 100 in the chamber 37 of the exhaust steam injector. The valve 38 is thereby moved to the right and the valve 39 opened. Also, the valve 30 is raised and pressed on its upper seat, so that a path is opened to the chamber 105 40 and also to the chamber 42 after the valve 41 has been displaced to the right. Steam flows from the chamber 40 under full boiler pressure into the live steam nozzle 49 and from the chamber 42 through holes 50 which 110 throttle the steam to the exhaust steam nozzle 46 down to the pressure of the exhaust steam. Water from the tender is now delivered over 115 the combining nozzle and the valve 43 to the pipe 9. From the pipe 9 the water passes to the pipe 13 and through the feed box 19 into the boiler. The two feeding processes take 120 place at the same time and entirely automatically after the valves 23 and 17 have been opened. In this working condition (1b) the arrangement represented in Fig. 1 has the following disadvantage if two feed boxes 19 and 22 are provided. The starting of the injector on opening the valve 17 causes a small 125 reduction of pressure in the pipes leading to

70

this valve, more particularly in pipe 11 and consequently also in pipe 12, and finally also in the container 18.

For this reason the boiler pressure may 5 keep the non-return valve in the feed box 22 closed and the hot water cannot flow from the container 18 to the boiler. This difficulty is obviated in the following manner: The delivery pressure of the feeding apparatus, 10 whether pump or injector, can always be so arranged that it exceeds the boiler pressure within definite limits. This excess of pressure energy is converted by a nozzle in the feed box into velocity which produces a fall 15 of pressure around the nozzle and is used for drawing down the hot water from the container. The feed pipe 20 from the hot water container is, therefore, led, according to the invention, to a combination feed valve which 20 also receives feed water from the injector and may be constructed, for example, as shown in Fig. 3. Any return of boiler water into the container which may be without pressure is prevented by a check valve 51. The 25 velocity of the water coming from the injector is increased by a nozzle 52, so that there is a fall of pressure in the annular space 53, which draws up the hot water from the container through the pipe 20. If 30 the control valve 23, Fig. 2, and the supplementary valve 17 are open so long that the container is emptied, the injector then feeds alone with live steam through the pipe 13 to the boiler. This corresponds then to the 35 working conditions denoted by 1c.

During the working conditions denoted by 2, with the locomotive regulator closed no feed is required. It is, therefore, only necessary to keep the control valve 23 and the supplementary valve 17 closed. A description 40 of the path of the steam in this case is unnecessary.

For the working condition indicated under 3, in which the locomotive regulator is open 45 and no feed is required, the valves 23 and 17 are also kept closed. Steam, however, flows from the valve chest through the pipe 4 to the pipes 5 and 6. Since the chamber 37 leading to the exhaust steam injector is not 50 under pressure, the valve 30 is pressed on its lower seat by the piston 31, and the valve 29 on its right hand seat. The chamber 37 is then under pressure which displaces the valve 38 to the right and thereby opens the 55 valve 39. The steam pressure now present in the chamber 37 is transmitted also through the opening, which is now free, of the upper seat of the valve 30 to the chamber 45, whereby the piston 32 is depressed and the exhaust 60 steam valve 33 is opened. The exhaust steam flows through the nozzle 46 and mixes in the adjoining combining nozzle with the water from the tender entering through valve 39, so that hot water flows past the valve 43 to 65 the pipe 9.

Since valve 23 is closed, valve 24 is kept open and there is a free path for the hot water through the pipe 14 to the container 18 which is not under pressure. The steam 70 from the slide valve chamber flows from pipe 4 through pipe 6 to valve 35 in the junction box 16. This valve 35 is pressed on to its seat and so prevents the steam from the slide valve chamber from flowing further.

The condition indicated under 4 occurs 75 when the locomotive regulator is open and water is to be delivered into the boiler. For this case, only the control valve 23 is to be opened and the valve 24 closed. The boiler pressure consequently present in chamber 44 80 has no further action on the valve 26, which rests by its own weight on its lower seating. The valve in this case cannot be raised, because there is the pressure of the slide valve chamber steam in the space above. 85

Boiler steam flows from the chamber 44 through the upper opening past the valve 26 into the chamber 48 and then into the pipe 8, displaces the valve 41 to its left position and enters by the live steam nozzle 49 into the injector. The other valves in the injector are 90 in the same position as described previously in connection with working conditions 3. The valve 39 and the exhaust steam valve 33 are open.

The difference merely consists in the live steam jet entering through the nozzle 49 which causes the mixture of steam and water flowing through the nozzles to overcome the boiler pressure. The water delivered 95 through the valve 43 flows through the pipe 9 to the junction box 16 and finds there, since the valve 23 is open, the path 14 to the container 18 closed by the valve 24, so that the water must flow through the pipe 13 and the feed box 19 to the boiler. 100

It is also possible in certain cases to utilize the injector as an independent feeding apparatus, more particularly if the container has been emptied and the steam valve is 110 closed.

What I claim is:—

1. In a boiler feed apparatus particularly for locomotives provided with working cylinders and a regulator controlling the supply of steam to the same, a cold water tank and a feeding device cooperating therewith capable of feeding water from said cold water tank into the boiler, means adapted to start and stop said feeding device and controlled by said locomotive regulator in such a manner that the feeding device can deliver only when the regulator is open, a hot water tank to collect water heated by exhaust steam from the cylinders, a feeding device capable of feeding said hot water from the hot water tank into the boiler, means adapted to start and stop the last named feeding device and controlled by the locomotive regulator in such a manner that starting of this feeding 125

- device is possible only when said regulator is closed, and further means comprising a hand operated valve controlling the steam flow along a path to which steam is admitted only when the locomotive regulator is closed, said steam operating the feeding device which feeds water from the cold water tank into the boiler.
2. In a boiler feed apparatus particularly for locomotives provided with working cylinders and a regulator controlling the supply of steam to the same, a cold water tank and a feeding device capable of feeding water from said cold water tank into the boiler, means adapted to start and stop said feeding device and controlled by said locomotive regulator in such a manner that the feeding device can feed only when the regulator is open, a hot water tank to collect water heated by exhaust steam from the cylinders, a feeding device capable of feeding said hot water from the hot water tank into the boiler, means adapted to start and stop the last named device and controlled by the locomotive regulator in such a manner that starting of this feeding device is possible only when said regulator is closed, and further special means adapted to operate the feeding device feeding water from said cold water tank to the boiler and comprising a hand operated valve controlling the flow of steam along a path to which steam is admitted only simultaneously with the operation of the feeding device capable of feeding water from the said hot water tank to the boiler.
3. In a boiler feed apparatus particularly for locomotives provided with cylinders and a regulator controlling the supply of steam to the same, a cold water tank and a feeding device capable of being operated by a supply of live steam thereto and feeding water from said cold water tank into the boiler, means controlled by said locomotive regulator in such a manner that it admits steam to said feeding device thus operating the same only when the regulator is open, a hot water tank to collect water heated by exhaust steam from the cylinders, a feeding device adapted to feed said hot water from the hot water tank into the boiler, means adapted to start and stop the last named feeding device and controlled by the locomotive regulator in such a manner that this feeding device can be started only when said regulator is closed, two separate paths for the live steam to the first named feeding device, one of said paths being controlled by the locomotive regulator so as to be automatically opened when the locomotive regulator is opened, and hand operated means adapted to admit steam into the second feeding path.
4. In a boiler feed apparatus particularly for locomotives provided with working cylinders and a regulator controlling the admission of steam thereto, a cold water container and a feeding device capable of feeding wa-
- ter from said cold water container into the boiler and of being operated by a supply of live steam thereto, a hot water container capable of storing water heated by exhaust steam from the cylinders and having its lowermost portion located above the high water level of the boiler, a feeding device to discharge the contents of said hot water tank into the boiler, a central control and change over apparatus controlling the operation of both feeding devices and comprising a master valve to be operated in order to feed the boiler with either device, a further device controlling discharge of the hot water tank into the boiler and controlled by the locomotive regulator, two live steam paths leading to the first named feeding device, a further means within said central control and change over device controlling one of said live steam paths, and a hand operated valve within said central control and change over device controlling the second path leading to the first named feeding device and capable of setting into communication said second path with a live steam supply controlled by the position of the regulator and being available only when said regulator is closed.
5. In a boiler feed apparatus particularly for locomotives provided with working cylinders and with a regulator controlling the supply of steam thereto, a cold water tank and a feeding device capable of being operated by a supply of live steam admitted thereto and feeding water from said cold water tank into the boiler, a hot water tank capable of being fed by said feeding device and adapted to collect the water fed, a feeding device to discharge the contents of said hot water tank into the boiler comprising a pipe for the admission of boiler pressure into said tank, means for controlling the passage through said pipe and being controlled by the locomotive regulator in such a manner that the passage through said pipe is open only when the locomotive regulator is closed, two live steam paths leading to the first named feeding device, automatic means controlled by the regulator for admitting live steam into one of said paths when the regulator is open, a hand operated device for opening the second live steam path and setting it into communication with a live steam carrying part, said part being simultaneously in connection with the supply of steam of boiler pressure for the hot water container, the supply of steam to said part being controlled by the locomotive regulator, the feeding device for feeding water from the cold water container into the boiler when operated arbitrarily by hand being thus only able to feed water into the boiler simultaneously with the feeding of water from the hot water container.
6. In a boiler feed apparatus particularly for locomotives provided with cylinders and

- a regulator for controlling the admission of steam to the same, a cold water tank, an injector adapted to be operated by exhaust steam and live steam for feeding water from 5 said cold water tank into the boiler while simultaneously heating the water fed, a hot water tank adapted to collect the water heated by exhaust steam, a feeding device for discharging the contents of said hot water 10 container into the boiler, a central change over device controlling said feeding apparatus, a master valve within said central change over apparatus to be operated whenever feeding from the cold water tank or from the 15 hot water tank into the boiler is to be initiated, a further valve associated with the master valve and controlling the feeding of water heated by exhaust steam to the hot water container, two live steam 20 paths leading to the exhaust steam injector, one of them controlled by a valve with two seats in the central change over device and adapted to prevent any admission of live steam through said path when the 25 locomotive regulator is closed, the other controlled by hand operated valve adapted to free the passage of live steam between said path leading to the injector and another path adapted to carry live steam to the feeding 30 device feeding water from the hot water tank into the boiler, means in said last named path controlled by the regulator in such a manner that this path and the live steam path leading via the manually operated valve 35 to the injector are kept open only when the regulator is closed, said means comprising the valve with two seats controlling the two above named live steam paths to the two feeding devices and alternatively moved against 40 one of its two seats by means of the pressure on the cylinder side of the locomotive regulator.
7. A boiler feed apparatus as claimed in claim 6 with a pipe leading to a point between 45 the locomotive regulator and the cylinder, an exhaust steam valve controlling the admission of exhaust steam to the exhaust steam injector, and a valve operating member adapted to be operated by the pressure within 50 in the above named pipe.
8. A boiler feed apparatus as claimed in claim 6 with a pipe leading to some point between the locomotive regulator and the cylinder and with a valve controlling the admission of auxiliary live steam supplementing the exhaust steam when not available, said valve being operated alternately by the steam pressure in the above named pipe and by the live steam pressure in the live steam path 55 leading to the exhaust steam injector and controlled by the hand operated valve.
9. A boiler feed apparatus as claimed in claim 6 with an exhaust steam injector provided with a live steam nozzle and an exhaust 60 steam nozzle, the latter arranged at the end 65 of an exhaust steam chamber, with a pipe leading to some point between the locomotive regulator and the cylinders, with a valve controlling the admission of auxiliary live steam supplementing the exhaust steam when not available, controlled alternately by steam of steam chest pressure admitted through the above named pipe and steam of boiler pressure admitted through one of the two live steam paths leading to the exhaust steam injector, a chamber within said injector, and a passage to said chamber controlled by a valve, said valve being operated by steam having the pressure of the steam chest, said chamber being provided with ports opening into the 70 exhaust steam chamber so as to reduce the live steam pressure admitted into the first chamber during the passage to the exhaust steam pressure.
10. A boiler feed apparatus according to 75 claim 6, wherein the exhaust steam injector is provided with a live steam nozzle and an exhaust steam nozzle, comprising a chamber for admitting the live steam, a separate chamber communicating with the first mentioned chamber leading to the live steam nozzle of the exhaust steam injector, a valve between both chambers to control the communication, said valve also controlling the admission of live steam to the chamber communicating 80 with the live steam nozzle by means of one of the two live steam paths leading to the exhaust steam injector, and closing the communication with the other chamber, when live steam is directly admitted to the said chamber.
11. A boiler feed apparatus according to 85 claim 6 wherein the exhaust steam injector is provided with a live steam nozzle and an exhaust steam nozzle, a chamber for admitting live steam, adapted to communicate with one of the live steam paths leading to the exhaust steam injector and with a steam path leading to the steam chest of the cylinders, a valve capable of controlling alternately the admission of live steam from one of said paths, a second chamber for admitting live steam and provided with ports capable of discharging said live steam under reduced 90 pressure into the room communication with the exhaust steam nozzle, a valve operated by steam of steam chest pressure controlling the admission of live steam to said second chamber, a further valve controlling the water admission of the injector, and a member within 95 said first chamber to actuate the same under the influence of pressure penetrating into said chamber.
12. A boiler feed apparatus according to 100 claim 6, wherein the exhaust steam injector is provided with a live steam nozzle and an exhaust steam nozzle, the live steam nozzle being fed from a chamber and said chamber being supplied with steam either from a second chamber or from the live steam path lead- 105

ing to the exhaust steam injector which is automatically controlled from the regulator, a valve alternately shutting one of said communications, a second valve controlling the admission of steam to said second chamber and operated by steam flowing from the locomotive regulator to the cylinders, another chamber supplied with steam either from the pipe carrying steam of the pressure prevailing between the locomotive regulator and the cylinder or from the second steam path leading to the exhaust steam injector, which is controlled by a hand operated valve, a water admission valve and an actuating member for the same arranged within said last named chamber, adapted to operate when pressure is admitted thereto, the live steam nozzle being either operated directly from one of said live steam paths when the regulator is open, thus providing the last named chamber with steam operating the water admission valve while closing the second chamber, or is operated by steam admitted through the other of the two live steam paths entering into the last named chamber and filling the second chamber and thereby also the first named chamber, when the regulator is closed and the hand operated valve is actuated.

13. A boiler feed device according to claim 2, with a common feeding head for the feeding paths from the cold water tank and the hot water tank allowing simultaneous feeding, and with means including a nozzle for drawing in the feed water flowing through one of said paths when its pressure is smaller than the pressure in the other path in order to ensure discharge of both feeding paths.

14. A boiler feed device according to claim 2, comprising common feeding head for the feeding paths from the cold water tank and the hot water tank allowing simultaneous feeding, means for drawing in the feed water flowing through one of said paths when its pressure is smaller than the pressure in the other path, said means including a nozzle in the path leading from the cold water tank and a non-return valve in the feeding path leading to the hot water tank.

In testimony whereof I affix my signature.
HANS DEUTSCH.
